ATTORNEYS

UNITED STATES PATENT OFFICE.

CLARENCE A. GODSHALK, OF PHILADELPHIA, PENNSYLVANIA.

FIREARM.

1,137,477.

Specification of Letters Patent. Patented Apr. 27, 1915.

Application filed November 12, 1914. Serial No. 871,652.

To all whom it may concern:

Be it known that I, CLARENCE A. GODSHALK, a citizen of the United States, residing at Philadelphia, county of Philadelphia, 5 State of Pennsylvania, have invented a new and useful Firearm, of which the following is a specification.

My invention relates to a new and useful improvement in fire arms and consists of 10 novel means for connecting the top rib with the barrel thereof.

It further consists of other novel features of construction, all as will be hereinafter fully set forth.

15 For the purpose of illustrating my invention, I have shown in the accompanying drawing certain forms thereof which will give in practice satisfactory and reliable results, although it is to be understood that changes 20 may be made and the arrangement varied which will come within the scope of the claims.

Figure 1 is a side elevation of a portion of a barrel and a portion of the top rib, embodying my invention. Fig. 2 is a top plan view thereof. Fig. 3 is a sectional view on line $x-x$ Fig. 1. Fig. 4 is a side elevation, on a reduced scale, of a portion of a barrel and top rib and showing a portion of the 30 frame and stop in dotted lines. Fig. 5 is a partial elevation partial sectional view of a portion of a barrel and top rib, showing another embodiment of my invention. Fig. 6 is a sectional view on line $y-y$ Fig. 5.

35 Heretofore it has been customary to rigidly connect the top rib of a fire arm with the barrel thereof throughout the length of the rib, or at intervals thereof, and, due to the expansion and contraction of the barrel 40 longitudinally, this has been found in some instances either to distort the top rib or else to cause the standards to break away from the barrel or from the top rib. My invention is designed to overcome this and to provide 45 means whereby the top rib is connected at one end rigidly with the barrel and at a suitable point or points is movably connected therewith in order to permit the expansion and contraction of the said barrel without 50 effect upon the top rib.

Similar numerals of reference indicate corresponding parts in the figures.

55 Referring to the drawings, 1 designates a portion of the barrel of a fire arm and 2 the breech end thereof. At a suitable point or points on the barrel I provide standards 3,

one end of each of which is rigidly connected with the barrel and the other end of which is movably connected with the rib, although this arrangement may be varied, if desired. 60 As here shown, the standards 3 are brazed or otherwise secured in any suitable manner to the barrel 1, and are movably connected with the top rib 4. This movable connection may be accomplished in many different ways, and in the drawings I have shown each standard provided with means for movable engagement with the top rib 4. As here shown, I have provided a groove or slot 5 in the standard which is preferably T-shaped. The top 65 rib 4 is suitably connected to the barrel adjacent the breech end 2 by soldering, electro-welding, brazing, or otherwise, and at suitable points on the rib 4, corresponding with the standards 3, I provide projecting members, here shown as headed pins or links 6, 70 each of which is suitably secured to the rib and movably connected with a standard 3, said pins being shaped to engage with and move in a slot 5 in a standard 3, whereby it 75 will be understood that while the rib is prevented from improper displacement, longitudinal movement is permitted between the barrel and rib and breakage of the parts is 80 prevented.

85 Another embodiment is shown in Figs. 5 and 6, wherein I have pivoted each of the links 7 at one end 8 to the rib 4 and at the other end 9 to a standard 3, with the same result as above described. It will be understood that the standard and rib are suitably 90 formed to accomplish the desired results.

95 It will now be apparent that I have devised a novel and useful construction of a fire arm which embodies the features of advantage enumerated as desirable in the statement of the invention and the above description, and while I have, in the present instance, shown and described preferred embodiments thereof which will give in practice 100 satisfactory and reliable results, it is to be understood that the same are susceptible of modification in various particulars without departing from the spirit or scope of the invention or sacrificing any of its advantages.

105 Having thus described my invention, what I claim as new and desire to secure by Letters Patent, is:—

110 1. In a device of the character stated, a barrel, a top rib having one end rigidly connected therewith, a standard rigidly connect-

- ed with said barrel, and means on said rib adapted to movably engage with said standard to hold the rib in position and to permit longitudinal movement between the parts.
5. 2. In a device of the character stated, a barrel, a top rib having one end rigidly connected with said barrel, and a plurality of standards rigidly connected with said barrel and in movable engagement with said rib to permit longitudinal movement between the parts.
10. 3. In a device of the character stated, a barrel, a top rib having one end suitably connected with said barrel, a plurality of standards connected with said barrel, projections on said rib having movable engage-
- ment with standards, whereby longitudinal movement of said rib with respect to said standards is permitted.
15. 4. In a device of the character stated, a barrel, a top rib having one end suitably connected with said barrel, a plurality of standards connected with said barrel, said standards having slots therein, and headed pins carried by said rib and each seated in a slot of a standard forming a movable engagement therewith.

CLARENCE A. GODSHALK.
